UNITED STATES PATENT OFFICE.

FELIX LANGE, OF ESSEN-ON-THE-RUHR, GERMANY, ASSIGNOR TO GOLDSCHMIDT
THERMIT COMPANY, OF NEW YORK, N. Y., A CORPORATION OF NEW YORK.

METHOD OF UNITING RAILWAY-RAILS.

1,153,435.

Specification of Letters Patent. Patented Sept. 14, 1915.

Application filed December 27, 1912. Serial No. 738,799.

To all whom it may concern:

Be it known that I, FELIX LANGE, a subject of the King of Prussia, and a resident of Essen-on-the-Ruhr, in the Province of the 5 Rhine, German Empire, have invented certain new and useful Improvements in Methods of Uniting Railway-Rails, of which the following is an exact specification.

In order to unite tramway-rails, an 10 aluminothermic welding method has been very widely practised, according to which method the rail ends were placed at a distance of about 15 to 20 millimeters apart and the intervening space was filled with 15 iron produced by the aluminothermic process. This method of uniting the rail ends resulted in a part of the rail ends being fused by the liquid iron poured into the intervening space aforesaid, so that in the 20 joint obtained the tread of the rail head was interrupted by a filling of aluminothermic iron, the length of which was about 6 centimeters. Now, practical experience has shown that the intermediate piece of aluminothermic iron generally becomes worn away to a greater extent than the rail itself. It has proved to be extremely difficult to 25 make the resistance capacity or durability of the aluminothermic iron filling equal to that of the rail itself but this disadvantage is overcome by the present invention.

The new or improved method of uniting rail ends consists in inserting into the space between the head portions of the rail ends 30 an intermediate piece of the same material as that from which the rails are formed and then performing the casting in the intermediate space in known manner. It has already been proposed to insert an intermediate 35 short length of rail into the space between the ends of two rails, the short length having the same cross section as the rails themselves, but it was impossible to obtain, according to this method a real homogeneous 40 union of the heads of the rail with the head of the inserted short length of rail, because the welding of the head was only effected by the slag resulting from the aluminothermic reaction.

45 The present method differs from the previous method inasmuch as the intermediate piece of metal inserted into the joint only covers part of the section of the rail head, whereas the whole remaining part of 50 the space is filled up with aluminothermic

iron. The improved method is carried out, for instance, in such a manner that a piece of metal of the same character as that from which the rails themselves are formed and corresponding more or less to the cross section of the heads of the rail ends is inserted 60 between the heads of the rail ends which are rigidly placed and are afterward surrounded by a mold. The inserted piece and the rail ends are then subjected to a preheating, as 65 described for instance in the specification of U. S. Patent No. 900,366 of 1908, and then liquid iron resulting from an aluminothermic or similar reaction is poured into the mold. The iron flows around the intermediate piece of metal and a perfect homogeneous union of the tread or head portion of the rail ends is obtained, and the said iron fills the remainder of the intermediate space 70 between the rail ends. In this way it is possible to introduce into the tread, which is subjected to wear and tear by the rolling stock, a material which has a capacity for resisting such wear and tear or a durability 75 equal to that of the rail itself.

To enable the mode of carrying the present invention into practice to be readily understood reference is made to the accompanying drawing which shows part of the section of a rail end which is to be joined to 80 a similar rail end together with the intermediate piece of metal which is inserted into the space between the end surfaces of the head portions of such rail ends.

In the drawing *a* is the rail end, *b* is the 85 inserted metal piece and *c* is the mold having holes *d* and *e* one of which may act as a pouring hole and the other as a riser in known manner.

The inserted piece *b* is somewhat of inverted L-shape but other shapes may be used. In the example shown the piece *b* is of such a shape and is so disposed as to lie between the thickest portions of the heads of the rail ends and so that its upper edge lies about 90 flush with or a little above the plane containing the actual tread surface of the rails. Thus the intermediate casting of liquid iron is limited to the web and foot of the rail and to the outer parts of the tread or head 100 of the rail.

The improved method presents still another advantage over the previous method above referred to for according to the latter it is necessary to subject the rail ends to a 110

pressing together, or so-called jumping action by means of a clamping device in order to obtain a good union. This drawing together of the rails is not necessary according to the present improved method but is replaced by the contraction of the iron forming a bulge around the rail and of the intermediate casting applied to the web and foot of the rail and to the exterior parts of the tread. It will be apparent from the drawing that there is no filling of cast metal in the actual tread surface which prevents an unbroken wearing face of wear-and-tear resisting metal owing to the presence of the upper edge of the metal piece *b* in the gap between the two rail ends.

What I claim is:

1. A method of uniting railway rails, which consists in inserting between the head portions only of the rails an intermediate piece of metal of such width as to extend across that part only of the heads of the rails which are subjected to wear by the car wheels and of a character corresponding to that of the metal from which the rails are formed, and then fusing said intermediate piece of metal together with the rail ends.

2. A method of uniting railway rails, which consists in inserting between the head portions only of the rails an intermediate piece of metal of such width as to extend across that part only of the heads of the rails which are subjected to wear by the car wheels and of a character corresponding to that of the metal from which the rails are formed, and then filling up the remaining part of the space between the rail ends with liquid iron.

3. A method of uniting rails, which consists in inserting between the head portions only of the rails, an intermediate piece of metal of less width than the head of the rail, and then pouring liquid metal into the space between the rails not occupied by said metal piece, whereby said metal piece is fused in position and the web and foot portions of the rails as well as the outer parts of the head portions of the rails are fused directly together by the liquid metal.

FELIX LANGE. [L. S.]
